(57) **CLAIM**

The ornamental design for a brush head for electric toothbrush as shown and described.

DESCRIPTION

FIG. 1 is a perspective view showing a first embodiment of a brush head for electric toothbrush design;
FIG. 2 is a front elevational view thereof;

FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a perspective view showing a second embodiment of a brush head for electric toothbrush design;
FIG. 9 is a front elevational view thereof;
FIG. 10 is a rear elevational view thereof;
FIG. 11 is a right side elevational view thereof;
FIG. 12 is a left side elevational view thereof;
FIG. 13 is a top plan view thereof;
FIG. 14 is a bottom plan view thereof;
FIG. 15 is a perspective view showing a third embodiment of a brush head for electric toothbrush design;
FIG. 16 is a front elevational view thereof;
FIG. 17 is a rear elevational view thereof;
FIG. 18 is a right side elevational view thereof;
FIG. 19 is a left side elevational view thereof;
FIG. 20 is a top plan view thereof;
FIG. 21 is a bottom plan view thereof;
FIG. 22 is a perspective view showing a fourth embodiment of a brush head for electric toothbrush design;
FIG. 23 is a front elevational view thereof;
FIG. 24 is a rear elevational view thereof;
FIG. 25 is a right side elevational view thereof;
FIG. 26 is a left side elevational view thereof;
FIG. 27 is a top plan view thereof;
FIG. 28 is a bottom plan view thereof;
FIG. 29 is a perspective view showing a fifth embodiment of a brush head for electric toothbrush design;
FIG. 30 is a front elevational view thereof;
FIG. 31 is a rear elevational view thereof;
FIG. 32 is a right side elevational view thereof;
FIG. 33 is a left side elevational view thereof;
FIG. 34 is a top plan view thereof; and,
FIG. 35 is a bottom plan view thereof.

The portions of the brush head for electric toothbrush shown in broken lines are included for the purpose of illustrating unclaimed portions of the brush head for electric toothbrush and form no part of the claimed design.
